DESIGN FOR A HAIR COMB

Daniel A. Adler, Glendale, Calif.

Application June 30, 1945, Serial No. 120,452

Term of patent 14 years

(Cl. D12—4)

To all whom it may concern:

Be it known that I, Daniel A. Adler, citizen of the United States, residing at Glendale, in the county of Los Angeles and State of California, have invented a new, original, and ornamental Design for a Hair Comb, of which the following is a specification, reference being had to the accompanying drawing, forming part thereof.

Fig. 1 is a perspective view of a hair comb showing my new design.

Fig. 2 is a side view in elevation of the comb of Fig. 1.

Fig. 3 is a plan view looking at the top of the comb.

I claim:

The ornamental design for a hair comb, substantially as shown,

DANIEL A. ADLER.
